G. M. VAN DYKE

COMBINED MUSIC RACK, HOLDER, AND TURNER

Filed August 20, 1924

UNITED STATES PATENT OFFICE.

GERALD MASON VAN DYKE, OF TIENSIN, CHINA.

COMBINED MUSIC RACK, HOLDER, AND TURNER.

Application filed August 20, 1924. Serial No. 733,201.

To all whom it may concern:

Be it known that I, GERALD M. VAN DYKE, a citizen of the United States, residing at Tientsin, China, have invented new and useful Improvements in Combined Music Racks, Holders, and Turners, of which the following is a specification.

This invention relates to improvements in combined music racks, holders and turners.

The principal object of this invention is to provide a holder for sheet music which will permit the ready turning of successive leaves of the music without fingering the same, thereby reducing to a minimum the possibility of dropping the music as now often happens.

Another object is to produce a device of this character which is adjustable and readily adapted to standard sizes of sheet music.

Another object is to produce a device of this character which may be employed in combination with standard makes of pianos or other musical instruments.

A further object is to produce a device which is economical to manufacture, simple in construction, neat in appearance, the parts of which are interchangeable and a device which may be readily assembled or disassembled.

Other objects and advantages will be apparent during the course of the following description.

In the accompanying drawings forming a part of this specification, and in which like numerals are employed to designate like parts throughout the same,

Figure 1 is a front elevation of my music holder,

Figure 2 is a cross section taken on the line 2-2 of Figure 1, partly broken away to show the manner of holding the music,

Figure 3 is a cross section taken on the line 3-3 of Figure 1, and

Figure 4 is a detail perspective view of one of the hinge units.

At the present time it is customary to stand a sheet of music upon the music rack and to grasp the sheet to be turned with the hand, with the result that the leaves are often dropped to the floor, which action causes an interruption in the playing as well as being inconvenient to the operator.

It is therefore my intention in producing this device to provide means whereby the person playing may readily turn the music

without any possibility of the same dropping to the floor.

In the accompanying drawings wherein for the purpose of illustration is shown a preferred embodiment of my invention, the numeral 5 designates a base-board having back portions 6 and 7 secured thereto, which back portions are connected by a bridge portion 8. The base 5 is cut away as shown at 9, and has secured therein a bearing 11. A bearing 12 is secured to the bridge portion 8 and is in alignment with the bearing 9. This arrangement permits a shaft 13 to extend through the bearings, which shaft supports the working parts of my device.

A collar 14 prevents the shaft 13 from dropping downwardly as it is held in place by a set screw 16. Slidably positioned upon the shaft 13 is a collar 17 held by a set screw 18. The collar is below the bridge portion 8 and serves to adjustably maintain sliders 19 and 21 upon the shaft 13. The construction of these sliders is best shown in Figure 4 where it will be noted that a lug 22 is bifurcated as shown at 23 so as to receive one end of an arm 24. This arm is provided with a downwardly extending nose 26 adapted to contact the underside of the lug 22 for the purpose of maintaining the arm 24 in a horizontal position.

A similar arm 27 is secured to the slider 21, each of which arms carries a pair of downwardly extending plates, as shown at 28 and 29. These plates are in turn provided with an orifice 31 adapted to receive the curved end 32 of a spring 33, the purpose of which will be later seen.

By again referring to Figure 4, it will be noted that a bent rod 34 is secured to the slider 19, and extends downwardly as shown at 36. This rod 34 is provided with an offset 37 for the purpose of accommodating the arm 27 when swung to its dotted line position of Figure 1. The slider 21 is provided with a rod 38 similar to the rod 34, which has a downwardly extending portion 39, but it will be noted that this rod has no offset therein. These rods 36 and 39 have their lower extremities telescoped by tubes 41 and 42, which tubes are secured to collars 43 and 44, respectively.

These collars are rotatable upon the shaft 13 and are held thereon by a collar 46 held in place by a set screw 47. Hand levers 48 and 49 are attached to the collars 44 and 43, respectively.

Spring clips 51 and 52 are attached to the back portions 6 and 7 for the purpose of holding the outside sheets of music.

The manner of operating my device is as follows:—

A sheet of music is placed upon the base board 5 and opened so that the front page may be clipped behind the spring 51, while the back page is clipped behind the spring 52. The middle pages are clipped beneath the spring 33 in the manner shown in Figure 2, which results in a portion of the sheet being pressed over the orifice 31. Should the pressure be insufficient to hold the spring in a simple manner it is possible to give the spring 33 a greater tension by slightly bending the same.

When it is desired the arms 24 and 27 may be swung to vertical position should it be found necessary to transfer the sheets of music due to the fact that they have become misplaced or for any other reason.

It will thus be seen that I have provided a very simple device which will accomplish all of the objects above set forth.

It is to be understood that the form of my invention herewith shown and described is to be taken as a preferred example of the

same, and that various changes in the shape, size and arrangement of parts may be resorted to without departing from the spirit of the invention or the scope of the subjoined claim.

Having thus described my invention, I claim:—

In a device of the character described, the combination with a base, of spaced back portions secured to said base, a shaft positioned between said back portions and secured to said base, a pair of sliders adjustably mounted on said shaft, a hinged arm secured to each of said sliders, downwardly extending clips secured to said arms, said clips having an orifice formed therein, springs mounted on said arms and adapted to have their free ends extending through the orifice in said clips, a pair of collars disposed on said shaft at a point below said base, hand levers secured to said collars, tubular extensions secured to said collars and extending upwardly, and rods extending from said sliders and having their free ends telescopically received in said tubular extensions, for the purpose specified.

In testimony whereof I affix my signature:
GERALD MASON VAN DYKE.
